UNITED STATES PATENT OFFICE.

GEORGE NIKOLOW, OF NEW YORK, N. Y.

DEVICE FOR CORING APPLES.

1,268,758.

Specification of Letters Patent.

Patented June 4, 1918.

Application filed April 15, 1918. Serial No. 228,670.

To all whom it may concern:

Be it known that I, GEORGE NIKOLOW, a citizen of the United States, residing at New York, in the county of New York and State 5 of New York, have invented certain new and useful Improvements in Devices for Coring Apples, and do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in devices for coring apples and consists of a simple and efficient device of this nature having various details of construction, combinations and arrangements 20 of parts which will be hereinafter fully described, shown in the accompanying drawings and then specifically defined in the appended claim.

25 My invention is illustrated in the accompanying drawings which, with the letters of reference marked thereon, form a part of this specification and in which:

Figure 1 is an elevation of the device part 30 being shown in vertical section.

Fig. 2 is a top plan view, and

Fig. 3 is a sectional view on line 3—3 of Fig. 1.

Reference now being had to the details of 35 the drawings by letter:

A designates a plate forming the base of the device, and A' is a platform supported above and spaced apart from the plate and is provided with a circular outlined aperture L. C is a cylindrical pin rising from 40 said plate and passing centrally through the aperture in the platform. Rising from said plate is a standard E carrying a pivotal pin F, upon which the arm H is pivoted. A spring N is fastened at its lower end upon 45 the upper side of said plate, and its other end is secured at O to the under surface of the arm H, the purpose of said spring being to support yieldingly said arm. Said arm

is provided with a series of perforations H', 50 forming means whereby the arm may be held in different positions relative to the pin F. Said arm has an integral hook K formed near its free end which is adapted to impale the apple, shown in dotted lines, and 55 hold the same over the pin C in readiness to have the core punched therefrom. The arm H, which has a handle H^s, is provided with a curved portion H², passing about a portion of the cylinder S in which the reciprocating 60 punch T works, and is fastened thereto in any suitable manner. The punch has a collar T⁴ thereon and which is adapted to limit its movement upwardly, and T⁵ is a coiled spring mounted within the cylinder 65 and bearing intermediate the bottom and said collar, and serving to hold the punch normally at its highest limit. A threaded cap S², fitted over the cylinder through 70 which the punch passes, has a longitudinal passageway T² therein with an exit end T³ where the cores are rejected.

In operation, the apple is placed upon the platform A' centrally over the pin C, after which the operator by taking hold of 75 the handle upon the arm, depresses the latter against the tension of the spring N. As the hook K comes in contact with the apple and further pressure is applied, the apple will be impaled by said hook and held in 80 proper position to have the core removed, which is accomplished by depressing the punch causing the same to pass through the center of the apple and telescoping over the pin. When pressure is removed from the 85 arm, the parts will return to their original positions and the operation may be repeated, each succeeding core serving to force the previous ones through the passageway T². 90

What I claim to be new is:

A device for coring apples, comprising a base with a cylindrical outline, a pin rising therefrom, a platform supported upon the base and provided with an opening through 95 which the pin projects, a spring pressed arm pivotally mounted upon said platform and terminating in a downwardly extend-

ing hook, a cylinder secured to said arm, a
spring pressed punch mounted in said cylin-
der, said hook adapted to hold and engage
the apple over the opening in the platform
5 while the core is removed by forcing the
punch through the apple and over said pin.

In testimony whereof I hereunto affix my
signature in presence of two witnesses.

GEORGE NIKOLOW.

Witnesses:

JOHN J. HOECKH,
FRED J. LOREY.
